Primary Examiner—Jeffrey D Asch
Assistant Examiner—Carla Jobe Wright(74) *Attorney, Agent, or Firm*—Oblon, Spivak, McClelland, Maier & Neustadt, L.L.P.(57) **CLAIM**

The ornamental design for an endpoint for videoconferencing, as shown and described.

DESCRIPTION

FIG. 1 is a top and left front perspective view of an endpoint for videoconferencing, showing the design;

FIG. 2 is a top and right front perspective view thereof;

FIG. 3 is a front view thereof;

FIG. 4 is a rear view thereof;

FIG. 5 is a bottom view thereof;

FIG. 6 is a top view thereof;

FIG. 7 is a left side view thereof; and,

FIG. 8 is a right side view thereof.

The broken lines that form the periphery of the unshaded rectangular region on the front of the endpoint for videoconferencing, shown in FIGS. 1-3 and 6, represent a boundary of the claimed design. The broken line showing of the handset, handset cradle, and small features on the rear and bottom of the endpoint for videoconferencing is for illustrative purposes only and forms no part of the claimed design. The broken lines and the unshaded regions that are defined by broken lines form no part of the claimed design.
